UNITED STATES PATENT OFFICE.

CORNELIS JOANNES HUGO PENNING, OF NEW YORK, N. Y.

COMBUSTION-ENGINE.

1,317,939.

Specification of Letters Patent.

Patented Oct. 7, 1919.

Application filed February 20, 1918. Serial No. 218,189.

To all whom it may concern:

Be it known that I, CORNELIS JOANNES HUGO PENNING, a subject of the Queen of the Netherlands, and a resident of New York, in the county of New York and State of New York, have invented certain new and useful Improvements in Combustion-Engines, of which the following is a specification.

10 This invention relates to combustion engines of the kind shown in my British Patent 12,068 of May 23, 1913, wherein the cylinders are arranged in pairs, each cylinder having two pistons, between which the 15 explosion occurs, the movement of the pistons being transmitted to a single crank shaft by means of rockers and connecting rods.

The object of this invention is to provide 20 improvements more especially applicable to two-cycle engines, and also various improvements in details of construction and oiling, whether of the type employing carbureters for forming the explosive charge, or of the 25 Diesel or semi-Diesel types.

In two-cycle engines embodying this invention, the casings inclosing the cylinders and moving parts are of such shape as to connect the open ends of each cylinder 30 through a communication passage running preferably parallel with the cylinder, forming pump spaces, and also isolate gas tight each pair of cylinders from one another, and from the crank shaft casing. The motor 35 consists of a main casting containing the cylinders and also part of the crank casing, together with top and bottom covers of such shape as to close the cylinder ends and also the crank casing.

40 The rockers are of such an improved shape as to have a gas-tight bearing surface against the main casting and covers. By this construction, a gas-tight partition is obtained in a plane running between the cylinders through crank shaft and rocker shafts. 45 The rocker is not necessarily supported in the bearing surfaces provided in covers and main casting but is preferably supported in roller or ball bearings placed in housings on the outside of the assembled housing. Caps 50 placed on these housings bind the main casting and covers together and keep dirt out and oil in.

To admit the explosive mixture from carbureter, or air, to the pump space, induction

ports are provided in the cylinder and are uncovered by one or both pistons at the end of the inward stroke. Each cylinder has an inlet port located to be uncovered by one piston about at the end of its working stroke, and an exhaust port located to be uncovered by the other piston just before the end of its working stroke. The inlet port of each cylinder is connected to the communication passage or pump space of that cylinder, so that the pistons charge the pump space on their inward stroke and compress such charge on their outward stroke until it is released into the open cylinder at one end through the inlet port. The cylinders are thus thoroughly scavenged from end to end and the fresh charge compressed during the succeeding inward stroke, and fired at the end of this stroke to drive the pistons outward. The ignition means 75 is placed between the innermost piston position, so as to be swept by the incoming scavenging charge.

A further feature of the invention consists in utilizing the pressure variations in the pump spaces for pumping lubricating oil from the cylinder whose pump space is under compression to the cylinder whose pump space is at the same time under reduced or sub-normal pressure.

In the accompanying drawings:

Figure 1 is a vertical section through both cylinders of one unit,

Fig. 2 is a vertical section taken at right angles to Fig. 1 through the crank shaft, 90 showing one cylinder in back ground,

Fig. 3 is a plan view with the top cover removed,

Fig. 4 is a section on the line 4—4, of Fig. 1,

Fig. 5 is a vertical elevation partly in section of a modification, showing the induction ports leading direct to crank case to which carbureter is fixed,

Fig. 6 is a side elevation of Fig. 5,

Fig. 7 is a section on the line 7—7 of Fig. 5, and

Fig. 8 is a top plan view of either form.

Referring to Figs. 1 to 4, 1 represents a vertical casing or main casting having supporting feet 2, showing a water jacket 3, a hole 4 for a spark plug between the pistons 5, in cylinders 6. Each cylinder has at one end an exhaust port 7, reversed as shown, and at the other end inlet ports 8 opening 110

into a communication passage 9 which runs from end to end of each cylinder connecting pump spaces 10. Thus when the pistons move outwardly simultaneously in either 5 cylinder they compress the charge for the next cycle in the spaces 10 for that cylinder and its communication passage 9. Each cylinder is separated from the other by 10 walls 11 in the detachable covers 16 at top and bottom, and by the bearing surfaces formed for the rockers between the main casting and covers. In these surfaces grooves with suitable packing can be arranged. Beyond the inlet ports 8 of each 15 cylinder are induction ports 12 which communicate with charge spaces 13 surrounding the cylinders, these induction ports 12 being opened simultaneously by the pistons when in extreme inward position, so that the 20 vacuum existing in the spaces 10 is filled by in-rush of air or charge from the spaces 13. A carbureter connection 14 is provided through the casing at any suitable point, and also a water connection 15, the other 25 water connection not being shown but being disposed at the other side at the lowest part of the water space. The pump spaces 10 are closed by hollow detachable covers 16 forming at the bottom oil wells 17 having 30 overflow holes 18 which discharge the oil into a bottom reservoir 19, thereby forming a cold oil well and also at the top forming a top oil reservoir for feeding the top rockers.

35 Each piston is connected by rod 20 with a rocker arm 21 mounted on a rock shaft 22, and the shafts 22 are each connected by a pitman 23 to the crank 24 or crank shaft 25, so that the four pistons work on one 40 crank. The crank shaft carries at one end a fly wheel 26 and at the other end a starting shaft 27. The pitman 23 is connected to the rock shaft 22 by means of disks 28 on the end thereof, one of which is provided 45 with a finished face 29 which is held against a coöperating finished face 30 on the casting so as to form a gas tight joint, the face 29 being shown as provided with grooves for suitable packing. A balance weight is provided 50 between these disks to counterbalance the weight of the pitman. A thrust bearing 31 and screw 32 are provided for regulating the bearing pressure so that there is no gas leakage.

55 The oil overflow from reservoir 17 runs into reservoir 19 from which pipes 33 provided with non-return valves lead to oil pipes 34 in the upper head, the pipes 33 being crossed as shown so that the pressure 60 in one chamber on one side forces the oil to the top of the cylinder on the other side which is at that time partly exhausted owing to the pistons being at their inner ends of travel, thus providing an automatic oil pumping system. The oil overflows from

the tops of the pistons down through the communication passage 9 to the bottom. This oiling system serves the cylinders and rockers and is strictly isolated from the crank casing. The crank shaft connecting 70 rods are oiled by splash lubrication, oil being kept in the crank case and thrown up by lower rocker arm balance weight.

In the modification shown in Figs. 5, 6 and 7, the carbureter or air inlet 14 is connected to the space 35 in which the connecting rods 22 work, and this space 35 is connected to the pump spaces and the cylinders 6 by induction ports 36, 37 being the communication passages. 38 is a deflector adjacent the opening 14 for preventing oil being thrown into carbureter.

If desired, an ordinary oil pump may be driven from crank shaft 25 through gears 40 and 41 driving pump 42, and gear 41 85 may also drive a gear 43 and a magneto shaft 44.

It will be seen that this engine is adaptable for various kinds of operation, but the compression for operating on the Diesel 90 principle will of course be higher than that for operating on relatively low compression where the charge is ignited by a spark or flame. An engine of this type can be built in as many units as desired, all arranged 95 parallel to each other and working on a common crank shaft. This engine has the advantage of providing large power in smaller spaces, eliminates valves, sleeves, or other distributing devices, and produces 100 complete scavenging of the cylinders from end to end without gas pockets. As herein shown, ball bearings are used throughout which is an advantage, and is possible herein owing to the loads being distributed and 105 the bearings being either in water cooled space, as for instance the main crank shaft bearing adjacent the crank, or else at portions of the cylinder which are normally cooled.

110 What is claimed, is:

1. A vertical combustion engine having parallel cylinders each having two oppositely movable pistons, a crank shaft extending transversely between said cylinders, 115 rockers pivoted between the ends of said cylinders and connected to the pistons, a connecting rod from one end of each rocker to the crank shaft, a communication passage connecting the opposite ends of each cylinder, the cylinder end spaces being proportioned to compress the charge during the working stroke of the pistons and being sealed by the rockers against leakage of charge outside the compression spaces, an inlet from each communication passage to the corresponding cylinder, opened by one piston at the end of its working stroke, an exhaust port at the other end opened by the other piston about at the end of its working 120 125 130

stroke, induction ports to the pump space controlled by said pistons at the end of the compression stroke, and a gas supply connected to said induction ports.

6. 2. An engine of the double cylinder two cycle rear compression type, each cylinder having two oppositely movable pistons connected to rockers, corresponding pistons being connected to the same rocker, and the 10 rockers to a crank shaft, the rockers being outside the rear compression spaces and having gas tight side bearings on the cylinder casting to prevent leakage of gas between the cylinder ends.

15. 3. An engine of the double cylinder two cycle rear compression type, each cylinder having removable heads and two oppositely movable pistons connected to a common crank shaft through rockers, covers for the 20 rockers, the said rockers, rocker covers, and cylinder body are so formed as to isolate gas tight the adjoining ends of the cylinders.

4. A combustion engine comprising two parallel cylinders with their ends each connected to a charge pumping space, oppositely moving pistons in each cylinder connected by rockers to a common crank shaft midway between the cylinders, the pumping space for each cylinder being isolated 30 from the other by a communication passage and a gas tight rocker packing.

5. A combustion engine comprising two parallel cylinders with their ends each connected to a charge pumping space, the pumping space for each cylinder being isolated 35 from the other, and one cylinder being oiled from the other by variations of pressure in said pumping spaces.

6. In a multiple cylinder engine having 40 the cylinders arranged in pairs, a pumping space at the end of each pair, the upper and lower pumping spaces being divided into chambers separated by gas tight partitions, the lower end also being horizontally divided so as to form upper level reservoirs 45 overflowing into lower reservoirs, and crossed oil leads from the lower reservoirs

to the upper portion of the opposite cylinder and arranged to raise oil by variations of pressure in said pumping spaces. 50

7. A combustion engine comprising two parallel cylinders with their ends each connected to a charge pumping space, two oppositely moving pistons in each cylinder so connected to a common crank shaft that one 55 cylinder is pumping on the rear sides of the two pistons while the rear sides of the pistons in the other cylinder are compressing, an oil reservoir below each cylinder, and cross oil connections between said oil reservoirs and the upper portions of said cylinders so that one cylinder is oiled by the compression in the other.

8. In a combustion engine having two cylinders each having a piston and a space 65 subjected to alternate compression and vacuum, an oil reservoir for each cylinder subject to similar pressure variations, and cross oil connections between each reservoir and the compression space of the other cylinder whereby to oil moving parts from said reservoirs by the pressure of one cylinder feeding oil to the other during the 70 vacuum of the latter.

9. A combustion engine comprising two 75 parallel cylinders having transverse bearings for a crankshaft midway of and between the cylinders, rocker bearings at each end between the cylinders, a rocker at each end, two pistons in each cylinder connected 80 to said respective rocker, said cylinders having reversed inlet and exhaust ports controlled by said pistons, connecting rods between said rockers and the crankshaft, oil retaining covers for the cylinder ends, a communication passage between the ends of each cylinder, and inlet ports to the ends of said cylinders outside said other ports and controlled by said pistons to admit charge to the 85 ends of said cylinders. 90

Signed at New York city, in the county of New York and State of New York this 13th day of February, A. D. 1918.

CORNELIS JOANNES HUGO PENNING.
